United States Patent Office

Des. 215,629
Patented Oct. 14, 1969

215,629

HOME AND GARDEN APPARATUS

Le Roy B. Carlson, Griswold, Iowa 51535

Filed June 28, 1968, Ser. No. 12,543

Term of patent 14 years

Int. Cl. D7—04; D11—02
U.S. Cl. D81—10

FIG. 1

FIG. 2

FIG. 3

FIG. 4

FIG. 5

FIG. 6

FIG. 7

FIG. 1 is a side elevation view of a home and garden apparatus showing my new design, as embodied in a barbecue grill;

FIG. 2 is a top plan view thereof;

FIG. 3 is a front elevational view thereof;

FIG. 4 is a rear elevational view thereof;

FIG. 5 is a side elevation view of a modified form thereof, as embodied in a planter;

FIG. 6 is a top plan view of the modified form thereof; and

FIG. 7 is a rear elevational view of the modified form thereof.

The elements shown in broken lines are included for illustrative purposes only.

I claim:

The ornamental design for a home and garden apparatus, substantially as shown and described.
